FALSE EYELASH APPLICATOR

Nathan L. Solomon, P.O. Box 550,
Englewood, N.J. 07231

Filed May 25, 1966, Ser. No. 2,430

Term of patent 14 years

(Cl. D86—10)

FIG. 1

FIG. 2

FIG. 3

FIG. 1 is a top perspective view of a false eyelash applicator showing my new design;

FIG. 2 is a side elevational view thereof;

FIG. 3 is a top plan view;

FIG. 4 is a bottom plan view;

FIG. 5 is a front elevational view;

FIG. 6 is a rear elevational view;

FIG. 7 is a side elevational view thereof in a closed position; and

FIG. 8 is a side elevational view of a second embodiment of the design shown in FIG. 1, wherein the top and bottom of the stop element are cylindrical and the spring end is rounded on the inner side.

I claim:

The ornamental design for a false eyelash applicator, substantially as shown and described.
